VAPOR AND LIQUID SEPARATOR

John Blizzard, Garden City, N. Y., Robert A. Lorenzini, Cranford, N. J., and Martin Frisch, New York, N. Y., assignors to Foster Wheeler Corporation, New York, N. Y., a corporation of New York

Application October 9, 1951, Serial No. 250,476

11 Claims. (Cl. 183—80)

1

This invention relates to the separation of fluids from mixtures thereof, and more particularly to the separation of vapor and liquid from mixtures of the same.

The invention will be disclosed as applied to the separation of steam and water in a drum of a water tube boiler, but it will be understood that the invention is not limited to this particular application but may be utilized generally in the separation of vapors and liquids from mixtures thereof.

In water tube boilers, mixtures of steam and water rise in the heated steam-generating tubes and discharge into drums wherein the steam separates from the water. The steam passes from the boiler through openings in the upper portion of the drum, while the water remaining in the drum recirculates through downcomers and the steam-generating tubes, in which latter tubes a portion of the water is evaporated and the separating process is repeated. In most boilers, particularly those which are operated at high specific rates of evaporation, the separation of water and steam is not complete and a portion of the water is carried off with the steam from the drum and a portion of the steam is carried back with the water to the boiler tubes. This incompleteness of separation is undesirable from the standpoint of superheating equipment and the steam-consuming equipment.

The present invention overcomes this disadvantage and provides separating apparatus in which steam and water or other vapors and fluids in admixture will be more completely separated in the steam drum or other enclosure.

The invention will be understood from the following description when considered in connection with the accompanying drawings forming a part thereof and in which:

Fig. 1 is a more or less diagrammatic view in transverse section of a steam and water drum of a steam generator having separating apparatus embodying the invention;

Fig. 2 is a longitudinal sectional view on a reduced scale taken on line 2—2 of Fig. 1;

Fig. 3 is a fragmentary plan view on a reduced scale taken on line 3—3 of Fig. 1;

Fig. 4 is a plan view, partly broken, of the separator embodying the invention;

Fig. 5 is a transverse sectional view taken on line 5—5 of Fig. 4; and

Fig. 6 is a rear view of the separator embodying the invention.

Like characters of reference refer to the same or similar parts throughout the views.

2

Referring to Figs. 1 to 3 of the drawings, reference numeral 10 designates a steam and water drum of a steam generator having a bank of steam-generating tubes 11 and downcomer tubes 12 connected at their upper ends to the lower portion of the steam and water drum. The drum, as shown, has two horizontal feed water pipes 13 and 14 extending longitudinally of the drum and disposed centrally within the drum in spaced relationship from a vertical plane passing through the longitudinal axis thereof.

A steam and water inlet passage is provided in the lower portion of the drum and, as shown, is formed by a curved sheet 15 comprising a number of segments 16 joined together by clamps 17 and running longitudinally of the drum a distance short of ends 18 and 19 thereof and in spaced relationship with the inner periphery 20 of the drum, thereby forming a curved steam inlet passage 21.

Curved sheet 15 is supported by end plates 22 and 23 which serve to close passage 21 in a fluid-tight manner at the opposite ends thereof. The end plates, which are coextensive with sheet 15, are of inverted L-shape, the horizontally extending legs thereof being secured to the underside of sheet 15 in a fluid-tight manner while the vertically extending legs are fastened in a fluid-tight manner, e. g., by welding, to the inner periphery of the drum. Steam and water passage 21 is closed along the top thereof at opposite sides of the drum by top plates 24 which extend from the inner peripheral surface of the drum to plate 15 and have a downwardly projecting leg 24' secured to plate 15 in a fluid-tight manner. The plates 24 extend longitudinally of the drum a distance coextensive with sheet 15, each of said top plates having a plurality of rectangular slots 24'' therein arranged in longitudinally spaced relationship. A rectangular-shaped flanged inlet sleeve 25 is secured to each of the top plates 24 by welding or similar means in such manner that each of the slots in the plates coincide with the passage in a sleeve.

It will be noted that steam generating tubes 11 discharge into steam and water inlet passage 21 and that the discharged steam and water is confined to said passage flowing upwardly therein toward top plates 24, while downcomer tubes 12 communicate with the opposite end portions of the drum outside enclosed steam inlet passage 21.

A plurality of steam and water separators which are spaced from one another longitudinally of the drum in the steam space thereof

is mounted on the top plates at opposite sides of said drum. The separators are spaced adjacent each other in rows running longitudinally of the drum and in spaced relationship with the inner periphery of the drum.

The steam and water separators are designated in the drawings by the reference numeral 26 and, as shown more particularly in Figs. 4 to 6, each comprises a container which is substantially an involute curve in cross section, the container having a peripheral plate 28 and opposite end members 29 and 30 spaced from one another axially of the container, the peripheral plate and end members forming between them a separation chamber 31 having a horizontal axis. A tangential steam and water inlet 32 is formed at one side of the separation chamber 31 by downwardly extending portion 33 of plate 28 and downwardly extending portions 34 and 35 of end members 29 and 30, respectively, together with an inner plate 36 spaced inwardly from portion 33 of plate 28 toward the separation chamber. The portion 33 of plate 28 and inner plate 36 are so arranged in relationship to one another as to form an inlet passage 37 which tapers in a direction toward the separation chamber. Inner plate 36 has a curved upper portion 37' which extends into the separation chamber, as shown, substantially 90°, said upper portion 37' of the inner plate being curved so as to provide, with plate 28, a gradual taper in the upper part of passage 37. The width of passage 37 is equal to the distance between end members 29 and 30 of separator 26.

A vertically extending, funnel-shaped water outlet conduit 38 communicates with separation chamber 31 at the bottom thereof, said water outlet conduit being formed at opposite ends thereof by extensions 39 and 40 of end members 29 and 30, respectively, and by a side member 41 adjacent tangential inlet 32. Water outlet 38 also has a curved side plate 42 spaced from side member 41, which curved side plate extends into separation chamber 31 a distance short of the inner edge of the curved upper portion 37' of inner plate 36 and in spaced relationship with peripheral plate 28 adjacent the bottom of the chamber, thereby providing an outlet 43. The distance between the inner edge of the curved upper portion 37' and the outlet 43, as shown is less than 180° while the distance between curved side plate 42 and plate 28 at opening 43 is approximately equal to the thickness at said opening of the layer of separated water flowing along peripheral plate 28 when the vapor generator is operating under full load conditions, as will hereinafter be fully described, so that substantially all the separated water will flow through outlet 43. A curved perforated baffle 44 extends across the mouth of water outlet conduit 38 and, as shown, has a knife edge 44' to reduce any disturbance at this point to a minimum. Baffle 44 defines the lower portion of separation chamber 31 and any separated water not flowing through outlet 43 will pass through baffle 44 into outlet conduit 38. A downwardly projecting extension 45 is joined to the lower portion of water outlet conduit 38 by a clamp 46. Tangential steam and water inlet 32 is flanged adjacent the inlet end thereof at 47 so that it may be attached to sleeve 25 by bolt 48 (see Fig. 1). A concave outlet guide plate 49 which extends longitudinally between end walls 29 and 30 is secured to curved side member 42 of the water outlet conduit at a point below outlet 43, said

baffle having connected to its lower end a curved extension 50, which extension is bolted to the guide plate 49 by a bolt 51.

Each of the steam and water separators 26 has circular steam outlet ports 52 in end members 29 and 30, which steam outlets are disposed substantially centrally of the separation chamber on the same longitudinally extending axis. Outlet ports 52 each are surrounded by an inwardly projecting lip 52' which prevents any drainage of water along end members 29 and 30 from passing outwardly through said ports.

As shown in Fig. 1, plate 15 is coextensive with substantially the lower half of drum 16 and terminates at a point substantially level with the normal water level WL in the drum. The various containers 26 are mounted on sleeves 25 with the longitudinal axis of the separation chamber 31 extending in a horizontal plane. Separators 26 are thereby positioned in the upper portion or steam space of drum 16 so that steam is discharged from the separators through steam outlets 52 into said steam space, and the separated water from the separators is discharged from the separators over guide plate 49 and extension 50 which extension is so adjusted on the guide plate that water flowing downwardly on the said guide plate and the extension, as hereinafter fully set forth, is discharged into the water space of the drum at the water level WL. Any separated water not so discharged from the separators will pass downwardly into the water in the drum below WL through extension 45 on the water outlet conduit.

Also disposed within the drum above the separators are a plurality of steam driers 53 extending transversely of the drum and in spaced relationship from the inner periphery of the drum and longitudinally a distance beyond the separators, said driers being supported by lugs 54 and bolts 55 secured to angle irons 56, welded or otherwise secured to the periphery of the drum. Dryer units 53 are V-shaped in cross section, each leg of which has a plurality of W-shaped plates 53' inserted therein in nested but spaced relationship with the apical edges of one plate within the area defined by the next adjacent plate, the drier as shown being of the chevron type as disclosed in U. S. Patent No. 2,472,101 granted to Martin Frisch on June 7, 1949. Entrained water particles carried over with the steam from the separator are separated therefrom as the steam and water mixture flows in the space between the nested plates, the separated water falling from said plates back into the water space of the drum. Above units 53 is disposed a substantially horizontal partition 57 extending laterally of the drum to angle irons 56 and longitudinally a distance equal to the length of trays 53, said partition being supported by rods 58 secured to the inner periphery of the drum by welding or like means and closed at its ends by arcuate plates 57' forming a steam chamber 57" having a plurality of small conduits 59 therein so as to form an outlet passage 60 for dried steam to pass out the drum by means of steam outlet pipe 61.

In operation, feed water is delivered to drum 16 at opposite sides of the longitudinal axis of the drum by feed water pipes 13 and 14 (Fig. 1) which direct said water substantially horizontally, through apertures in the pipes, toward said longitudinal axis. The flow of feed water into the drum is so regulated that the level thereof is maintained at a normal water level, WL. Feed

water flows downwardly from the drum through downcomers 12 (Fig. 2) into steam-generating tubes 11, in which a mixture of steam and water is generated, said mixture flowing from steam-generating tubes into steam inlet passage 21 wherein it passes upwardly. The upwardly flowing mixture of steam and water enters inlet sleeves 25 at opposite sides of the drum whence it passes into inlet passages 37 of the separators 26, which are, as shown, spaced from one another in rows extending along opposite sides of the drum 10.

The mixture of steam and water is delivered tangentially of separation chamber 31 of each of the separators 26 through tapered rectangular-shaped inlet passage 37, at a high velocity. A curved path of flow around a horizontally extending axis is imparted to the mixture by that portion of inlet passage 37 bounded by upper portion 37' of the inner plate 36 and peripheral plate 23. The mixture entering separation chamber 31 will follow the curvature of peripheral plate 23 in a thin sheet. Because of the difference in densities of the steam and water in said mixture, separation occurs through the action of centrifugal force and a relatively thin layer of water is formed which travels along the inner periphery of plate 23 toward outlet 43. As the mixture turns on a horizontal axis in separation chamber 31 for a distance less than a complete revolution in said chamber, steam flows therefrom inwardly toward the center of the separation chamber and thence passes outwardly therefrom in a longitudinal direction through steam outlets 52 into the space in the steam drums between adjacent steam and water separators 26. Since the layer of water on the inner periphery of peripheral plate 23 is thin, separation of steam therefrom is very rapid. The separated water passes through outlet 43 and engages concave outlet guide plate 49, which causes the separated water to flow in a circular direction opposite that in which it flows in separation chamber 31. Separated water passes from guide plate 49 onto extension 50, from which it is passed onto the surface of the water in a direction toward the center of the drum at WL. Should the thickness of the stream of separated water flowing into outlet 43 be greater than the distance between peripheral plate 23 and curved side plate 42 of water outlet 43, a portion of said separated water will flow onto perforated baffle 44, thence through the perforations therein into water outlet conduit 38. The separated water flows through extension 45 into the lower portion of drum 10.

Separated steam which leaves separators 26 through outlet ports 52 passes upwardly into the upper portion of drum 10, thereafter flowing through steam dryer units 53, wherein any remaining moisture in the steam is removed. From trays 53 the dried steam flows outwardly of drum 10 through outlet pipe 61.

In accordance with the invention, it will be perceived that the component parts of the vapor-liquid mixture are completely separated readily and efficiently and without necessity for utilization of cumbersome arrangements. The operation is such that dried vapor is obtained while vapor-free liquid is delivered to the vaporizing tubes of the generator. Also, a steam and water separator is provided which will function with a higher water level in the vapor and liquid drum of a vapor generator.

It will be understood that changes may be made in the form, location and arrangement of

the several parts of the apparatus illustrated, without departing from the principles of the invention. The invention is not to be limited except by the scope of the appended claims.

5 What is claimed is:

1. In a vapor and liquid drum of a vapor generator having a liquid space in the lower portion of the drum with a predetermined liquid level therein and a vapor space in the upper portion 10 of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, tangential inlet-forming means in communication with said inlet compartment and with the separating chamber tangentially thereof and so that a mixture of liquid and vapor from said inlet will impinge on the inner peripheral surface of the chamber and follow the curvature thereof, said chamber having a longitudinally extending liquid outlet in the periphery thereof, said liquid outlet being disposed from said inlet circumferentially of the casing a sufficient distance to permit vapor and liquid to be separated from a mixture thereof by centrifugal force in its curved path of flow in the separating chamber, the separating chamber being so located in the drum that the outlet is above said water level and the vapor outlet opening communicates with the vapor space of the drum, and a curved guide member extending longitudinally of the separating chamber at the liquid outlet, said guide member being curved reversely of the curve of said chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

2. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the cham-

ber having a vapor outlet opening in at least one end thereof in communication with said vapor space, tangential inlet-forming means in communication with said inlet compartment and with the separating chamber tangentially thereof and so that a mixture of liquid and vapor from said inlet will impinge on the inner peripheral surface of the chamber and follow the curvature thereof, said chamber having a longitudinally extending liquid outlet in the periphery thereof, said liquid outlet being disposed from said inlet circumferentially of the casing a sufficient distance to permit vapor and liquid to be separated from a mixture thereof by centrifugal force in its curved path of flow in the separating chamber, the separating chamber being so located in the drum that the outlet is above said water level and the vapor outlet opening communicates with the vapor space of the drum, and a curved guide member extending longitudinally of the separating chamber at the liquid outlet, said guide member being curved reversely of the curve of said chamber and projecting downwardly therefrom with one longitudinal edge thereof spaced inwardly of said periphery toward the center of the chamber such distance as to provide said periphery of the chamber with an outlet opening of such dimension at said outlet opening so that separated liquid flowing from the chamber through the liquid outlet passes onto the reversely curved surface of the guide member, the opposite longitudinal edge of the guide member being so located that liquid therefrom is discharged into the liquid space of the drum at said liquid level.

3. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, a substantially vertically extending tangential inlet-forming means in communication with said inlet compartment and with the separating chamber tangentially and at one side thereof and so that a mixture of liquid and vapor from said inlet will be directed upwardly and inwardly of the separating chamber to impinge on the inner peripheral surface of said chamber and follow the curvature thereof, said chamber having a longitudinally extending liquid outlet in the periphery thereof, said liquid outlet being disposed from said point of impingement of the mixture on said periphery a distance less than 360° but sufficient to permit vapor and liquid to be separated from a mixture thereof by centrifugal force in its curved path of flow in the chamber, the separating chamber being so located in the drum that the outlet is above said water level and the vapor outlet opening communicates with the vapor space of the drum, and a curved guide member extending longitudinally of the chamber at the liquid outlet, said guide member being curved reversely of the curve of the separating chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

space of the drum, and a curved guide member extending longitudinally of the chamber at the liquid outlet, said guide member being curved reversely of the curve of the separating chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

4. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, a substantially vertically extending tangential inlet-forming means in communication with said inlet compartment and with the separating chamber tangentially and at one side thereof and so that a mixture of liquid and vapor from said inlet will be directed upwardly and inwardly of the separating chamber to impinge on the inner peripheral surface of said chamber and follow the curvature thereof, said inlet-forming means decreasing in cross-sectional area in the direction of flow of said mixture and having an outlet portion extending into and curved in the same direction as said chamber, the separating chamber having a longitudinally extending liquid outlet in the periphery thereof, said liquid outlet being disposed from said point of impingement of the mixture in said periphery a distance less than 360° but sufficient to permit vapor and liquid to be separated from a mixture thereof by centrifugal force in its curved path of flow in the chamber, the separating chamber being so located in the drum that the outlet is above said water level and the vapor outlet opening communicates with the vapor space of the drum, and a curved guide member extending longitudinally of the chamber at the liquid outlet, said guide member being curved reversely of the curve of the separating chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

5. In a vapor and liquid drum of a vapor generator having a liquid space in the lower portion of the drum with a predetermined liquid level therein and a vapor space in the upper portion

of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, a substantially vertically extending tangential inlet-forming means in communication with said inlet compartment and with the separating chamber tangentially and at one side thereof, said inlet-forming means decreasing in cross-sectional area in the direction of flow of said mixture and having an outlet portion extending into and curved in the same direction as said chamber, the chamber having a longitudinally extending liquid outlet in the periphery thereof and spaced from said vertically extending inlet-forming means circumferentially of the casing a sufficient distance to permit vapor and liquid to be separated from a mixture thereof by centrifugal force in its curved path of flow in the separating chamber, the separating chamber being so located in the drum that the outlet is above said water level and the vapor outlet opening communicates with the vapor space of the drum, a curved guide member extending longitudinally of the chamber at said liquid outlet, the guide member being curved reversely of the curvature of the separating chamber and projecting downwardly therefrom with one longitudinal edge in spaced relationship with said inlet-forming means and spaced inwardly toward the center of the chamber such distance as to provide with the inner periphery of the chamber an outlet opening of such dimension at said outlet opening so that separated liquid flowing along the inner periphery will pass outwardly of the chamber through the liquid outlet, the opposite longitudinal edge of the guide member being so located that liquid therefrom is discharged into the liquid space of the drum at said liquid level, and surplus water outlet means in communication with said chamber and projecting downwardly therefrom in the space between said liquid outlet and said inlet-forming means.

6. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, said inlet compartment extending longitudinally of the drum and having vapor and liquid mixture outlets at opposite sides of the longitudinal axis thereof, vapor and liquid separating means in the vapor space of the drum in communication with the vapor and liquid outlets of said compartments, said separating means being spaced from one another axially of the drum, each separating means comprising a cas-

ing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, a substantially vertically extending tangential inlet-forming means in communication with said inlet compartment and with the separating chamber tangentially and at one side thereof and so that a mixture of liquid and vapor from said inlet will be directed upwardly and inwardly of the separating chamber to impinge on the inner peripheral surface of said chamber and follow the curvature thereof, said chamber having a longitudinally extending liquid outlet in the periphery thereof, said liquid outlet being disposed from said point of impingement of the mixture on said periphery a distance less than 360° but sufficient to permit vapor and liquid to be separated from a mixture thereof by centrifugal force in its curved path of flow in the chamber, the separating chamber being so located in the drum that the outlet is above said water level and the vapor outlet opening communicates with the vapor space of the drum, and a curved guide member extending longitudinally of the separating chamber at the liquid outlet, said guide member being curved reversely of the curve of the separating chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

7. Vapor and liquid separating means for separating vapor and liquid from a mixture thereof, said separating means comprising a casing forming a generally cylindrically-shaped separating chamber positioned with the longitudinal axis thereof extending in a substantially horizontal plane, the chamber having a vapor outlet opening in at least one end thereof, substantially vertically upwardly extending tangential inlet-forming means in communication with a source of said mixture and with the separating chamber tangentially and at one side thereof and so that a mixture of liquid and vapor from said inlet will be directed upwardly and inwardly of the separating chamber to impinge on the inner peripheral surface of the chamber and follow the curvature thereof, said inlet-forming means decreasing in cross-sectional area in the direction of flow of said mixture and having an outlet portion extending into the chamber at the upper part thereof and curved in the same direction as said chamber, the separating chamber having a longitudinally extending liquid outlet in the lower portion of the periphery thereof and spaced circumferentially from said point of communication of the inlet-forming means with said separating chamber, the space in the chamber between said point of communication of the inlet-forming means and said liquid outlet being open to communicate with the central portion of the chamber, and a guide member extending longitudinally of the chamber and downwardly at the liquid outlet, said guide member being spaced inwardly of said inner periphery toward the center of the chamber and projecting outwardly and

downwardly of the chamber and away from said outlet, the guide member being spaced inwardly toward the center of said chamber such distance that separated liquid flowing along the inner periphery of the separating chamber will pass outwardly of the chamber through the liquid outlet.

8. Vapor and liquid separating means for separating vapor and liquid from a mixture thereof, said separating means comprising a casing forming a generally cylindrically-shaped separating chamber positioned with the longitudinal axis thereof extending in a substantially horizontal plane, the chamber having a vapor outlet opening in at least one end thereof, substantially vertically upwardly extending tangential inlet-forming means at one side of the separating chamber and in communication with a source of said mixture and with the separating chamber tangentially thereof and so that a mixture of liquid and vapor from said inlet will be directed upwardly and inwardly of the separating chamber and will impinge on the inner peripheral surface of the chamber and follow the curvature thereof, said inlet forming means decreasing in cross-sectional area in the direction of flow of said mixture and having an outlet portion extending into the chamber at the upper part thereof and curved in the same direction as said chamber, said outlet portion extending into the chamber a distance sufficient to impart a curved movement to the mixture introduced into the chamber, said chamber having a longitudinally extending liquid outlet in the lower portion of the periphery thereof and spaced circumferentially from said outlet portion of the inlet-forming means and from said vertically extending inlet forming means, a curved guide member extending longitudinally of the chamber at said liquid outlet, the guide member being curved reversely of the curvature of the separating chamber and projecting downwardly therefrom with one longitudinal edge in spaced relationship with said inlet forming means and spaced inwardly toward the center of the chamber such distance as to provide with the inner periphery of the chamber an outlet opening of such dimension at said outlet opening so that separated liquid flowing along the inner periphery will pass outwardly of the chamber through the liquid outlet, and surplus water outlet means in communication with said chamber and projecting downwardly therefrom in the space between said liquid outlet and said inlet-forming means.

9. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a generally cylindrically-shaped separating chamber positioned in the vapor space of the drum with the longitudinal axis thereof extending in a substantially horizontal plane, the chamber having a vapor outlet opening in at least one end thereof in communication with said vapor space, tangential inlet-

forming means in communication with said inlet compartment and with the separating chamber tangentially thereof and so that a mixture of liquid and vapor from said inlet will impinge on the inner peripheral surface of the chamber and follow the curvature thereof, said inlet-forming means decreasing in cross-sectional area in the direction of flow of said mixture, the separating chamber having a longitudinally extending liquid outlet in the periphery thereof, said liquid outlet being disposed from said inlet circumferentially of the casing a sufficient distance to permit vapor and liquid to be separated from a mixture thereof by centrifugal force in its curved path of flow in the separating chamber, the separating chamber being so located in the drum that the outlet is above said water level and the vapor outlet opening communicates with the vapor space of the drum, and a curved guide member extending longitudinally of the separating chamber at the liquid outlet, said guide member being curved reversely of the curve of said chamber and projecting downwardly therefrom with one longitudinal edge thereof spaced inwardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

10. In a vapor and liquid drum of a vapor generator having a liquid space in the lower portion of the drum with a predetermined liquid level therein and a vapor space in the upper portion of the drum above said liquid level, partition means providing an inlet compartment separate from said liquid and vapor spaces of the drum and into which a mixture of vapor and liquid from the vapor generator is discharged and through which said mixture flows to said vapor space, vapor and liquid separating means in the vapor space of the drum and located in the path of flow of said mixture of vapor and liquid from the compartment to said vapor space, said separating means comprising a casing forming a separating chamber in the shape of an involute curve in transverse cross-section, said chamber being positioned with the longitudinal axis thereof extending in a substantially horizontal plane, the chamber having a vapor outlet opening in at least one end thereof in communication with said vapor space, tangential inlet-forming means in communication with said inlet compartment and with the separating chamber tangentially thereof and so that a mixture of liquid and vapor from said inlet will impinge on the inner peripheral surface of the chamber and follow the curvature thereof, said chamber having a longitudinally extending liquid outlet in the periphery thereof, said liquid outlet being disposed from said inlet circumferentially of the casing a sufficient distance to permit vapor and liquid to be separated from a mixture thereof by centrifugal force in its curved path of flow in the separating chamber, the separating chamber being so located in the drum that the outlet is above said water level and the vapor outlet opening communicates with the vapor space of the drum, and a curved guide member extending longitudinally of the separating chamber at the liquid outlet, said guide member being curved reversely of the curve of said chamber and projecting downwardly therefrom with one longitudinal edge thereof spaced in-

13

wardly of said periphery toward the center of the chamber such distance that liquid flowing from the chamber through the liquid outlet passes onto the reversely curved surface of the guide member, the opposite longitudinal edge of the guide member being so located that liquid therefrom is discharged into the liquid space of the drum at said liquid level.

11. Vapor and liquid separating means for separating vapor and liquid from a mixture thereof, said separating means comprising a casing forming a separating chamber in the shape of an involute curve in transverse cross-section, said chamber being positioned with the longitudinal axis thereof extending in a substantially horizontal plane, the chamber having a vapor outlet opening in at least one end thereof, substantially vertically upwardly extending tangential inlet-forming means in communication with a source of said mixture and with the separating chamber tangentially and at one side thereof and so that a mixture of liquid and vapor from said inlet will be directed upwardly and inwardly of the separating chamber to impinge on the inner peripheral surface of the chamber and follow the curvature thereof, said inlet-forming means decreasing in cross-sectional area in the direction of flow of said mixture and having an outlet portion extending into the chamber at the upper part thereof and curved in the same direction as said chamber, the separating chamber having a longitudinally extending liquid outlet in the lower portion of the periphery thereof and spaced

14

circumferentially from said point of communication of the inlet-forming means with said separating chamber, the space in the chamber between said point of communication of the inlet-forming means and said liquid outlet being open to communicate with the central portion of the chamber, and a guide member extending longitudinally of the chamber and downwardly at the liquid outlet, said guide member being spaced inwardly of said inner periphery toward the center of the chamber and projecting outwardly and downwardly of the chamber and away from said outlet, the guide member being spaced inwardly toward the center of said chamber such distance that separated liquid flowing along the inner periphery of the separating chamber will pass outwardly of the chamber through the liquid outlet.
